UNITED STATES PATENT OFFICE.

EDGAR F. PRALE, OF SARANAC LAKE, NEW YORK.

GAS-ENGINE.

1,071,342.

Specification of Letters Patent. Patented Aug. 26, 1913.

Application filed August 23, 1912, Serial No. 378,591.

To all whom it may concern:

Be it known that I, EDGAR F. PRALE, a resident of Saranac Lake, in the county of Franklin and State of New York, have invented certain new and useful Improvements in Gas-Engines; and I do hereby declare the following to be a full, clear, and exact description of the invention, such as will enable others skilled in the art to which it pertains to make and use the same.

This invention relates to gas engines of the type having a main outer casing, a stationary inner drum, and a plurality of pistons movable in the annular chamber between the casing and drum, and rotary abutment valves in semi-circular extensions of the casing.

The object of the invention is to improve the construction of such engines, and to increase their efficiency, and more particularly by providing simple and improved cooling means.

The invention consists in the construction hereinafter described and particularly pointed out.

In the drawing which illustrates the invention and forms part of the specification,—Figure 1 is a vertical longitudinal central section of the engine; Fig. 2 is a vertical transverse section of the engine, the section being taken with the abutment valves advanced from the position shown in Fig. 2 to a position in which the heads stand at the same level; Fig. 3 is a side elevation of the same; Fig. 4 is a side elevation, with a part removed, showing a modified construction.

Numerals 1, 2, denote the main end portions of the casing of the engine, which are either cast integrally with the main cylinder or separately and secured thereto. Said ends comprise at diametrically opposite sides semi-circular extensions 3, 3, which form the ends of chambers for rotary abutment valves, the chambers being completed by cover portions 4 secured between the ends.

In a central opening in end 1 is firmly supported a strong, hollow, stationary sleeve 5, within which the main shaft 6 rotates, ball bearings being provided for the shaft within caps 7, fixed to the casing ends.

A gear wheel 8 is secured on the main shaft, and wheels 9, 10, of the same size as wheel 8, are secured to the shafts of the rotary abutment valves 11, 12, whereby the lat-

ter are suitably timed for the passage of the pistons.

The engine casing is formed at each end with circular flanges 13, 14, surrounding the main shaft, the space between them being closed at each end by a ring 15 bolted to the casing. The casing is also formed with straight longitudinal side flanges 16 which extend the entire distance between rings 15. Curved outer plates 17 are bolted to the flanges 16, and form a closed chamber or passage 18, designed for reception of a cooling liquid or fluid, as water, oil or air. The cooling chamber is continuous on the sides and over the ends of the engine body.

It is not essential that the outer walls 17 be plates separate from the main body casting though this is preferred.

Supported in a fixed position on the sleeve 5 is a central drum 19, concentric with the main shaft and with the piston chamber 20, between the drum and the casing. The ends of the drum are circular, and are either cast with the body of the drum, as shown at 21, or made as separate rings and attached to the drum, as shown at 22. Evidently both ends of the drum may be formed alike if desired. One advantage of having the end ring (or rings) detachable is that, when an end of the main casing is removable, it permits the withdrawal of the abutment valves without taking the machine all apart. The body of the drum between the end rings is cylindrical except that on the sides facing the abutment valves are concavities 23, of the same radii and centers as the abutment valves, and through which the closely fitting heads of the abutment valves pass. The drum 19 is formed with a large annular chamber 24, and preferably with deep annular grooves 25 at its ends, with connecting holes 26. In some cases the holes 26 may be omitted, in which case an outlet for the cooling fluid would connect with chamber 24. The ends of the piston structure are likewise perforated at 26 so that the cooling fluid may pass to the outer sides thereof.

The main shaft is grooved, reduced, or otherwise formed within a part of the length of the sleeve 5 to form a passage 27 for the cooling medium, said passage being connected at one end to the hollow 24 of the drum, and at the other end to the space surrounding the main casing by holes 28. On the shaft outside both ends of passage 27 are

100
105
110
115

packings 29 to prevent leaking along the shaft. The inlet and outlet openings for the cooling medium may be at any suitable places. In Fig. 1, 29^x indicates such inlet, 5 and 29^y an outlet, the cooling medium thus flowing entirely through the engine. In practice a second outlet communicating with the opposite end space would be advisable but it is not shown. The connection of the 10 outer and inner cooling spaces causes the most perfect utilization of the cooling medium, and requires but a single source of circulation and a single passage between the source and the cooling chambers.

15 The piston structure comprises two circular ends 30, 31, the former rotatably mounted on the fixed sleeve 3, and the latter rigidly secured to the main shaft, as by lugs 32 on the shaft and bolts, whereby the 20 piston structure is supported at both ends and has only one friction bearing. Connecting the ends at diametrical points are two pistons 33, 34, with inner and outer spring packings 34^x, see Fig. 2. The ends 25 of the piston structure have outer and inner flanges 35, 36, the latter overlapping the end rings of the drum 19, and between the abutting faces is a packing 37, preferably spring ring packing, and is in the periphery 30 of the drum rather than in its end. The ends of the piston structure have like peripheral packings 38. Each abutment valve comprises two curved sides or heads 39, separated by concavities 40, each occupying 35 approximately a quadrant of the abutment chamber. The abutment valves in rotating enter the concavities 23 in the drum, and the concavities 40 allow the pistons to pass. In practice the heads and ends of the abutment valves are preferably provided with packings, as shown in my application 553,563, filed April 5, 1910.

In Fig. 2, 41 denotes the inlet to the piston chamber for the gas or explosive mixture, and 42 the exhaust, separated by the pistons. Over the upper abutment chamber is a concentric cap forming a compression chamber 43, communicating at one side with the abutment chamber, near the piston 50 chamber, by a passage 44 which is opened and closed by the abutment valve as the latter rotates. At the opposite side there is a similar passage but which has a controlling valve 45 moved in any suitable manner, such as by equal cam wheels 50, 51, on the abutment valve shaft, and on the stem of valve 45. For causing explosions at proper times an igniting device of any suitable construction is denoted by 46, Fig. 3, 55 and the explosion chamber by 47, Fig. 2.

In the construction shown in Fig. 4, the engine casing, and the outer wall of the cooling chamber, including the end rings, are made in halves (the upper halves being 60 removed in said figure). The parts are se-

cured together by suitable means, such as lugs or flanges 48 and bolts. This gives easy access to the piston structure.

Operation: As the lower piston moves up it compresses the explosive mixture ahead of it into chamber 43, the upper abutment valve opening the passage, and another charge is drawn in behind said piston. Simultaneously valve 45 is opened admitting compressed explosive mixture into chamber 47, behind the upper piston, when valve 45 becomes closed, and the explosion occurs, driving said piston down, and so on repeatedly. The heat developed is reduced and dissipated by the cooling medium which entering at 29^x flows through the large space surrounding the sides and ends of the engine cylinder, through passages 28 to passage 27 around the main shaft, thence to the hollow 24 of the central drum, to the end grooves 25, thence to the outer sides of the ends of the piston structure, and thence out by passage 29^y. When the cooling medium is a liquid, as water or oil, it serves also to improve the closure of the piston chamber, since if gas should escape by the ring packings of drum 19 and of the piston structure it would still have to pass through such liquid, at the same time the packings would be sufficient to keep liquid from the abutment chambers.

Having described the invention what I claim and desire to secure by Letters Patent is,—

1. A gas engine comprising a main casing 100 having a gas inlet and an exhaust, and opposite rotary abutment valve extensions, a double headed abutment valve in each extension, said inlet and exhaust being adjacent one valve extension, a compression chamber adjacent the other valve extension, and means suitably controlled admitting gas to said chamber and for taking gas therefrom to the explosion chamber, said explosion chamber, a stationary drum with in and concentric with the casing body, a main shaft, a piston structure thereon comprising circular ends connected by opposite pistons adapted to travel in the space between the casing and drum, and to pass said abutment valves, and said explosion chamber being behind one of the pistons, outer walls forming a chamber for a cooling medium around the main casing body, the stationary drum having a hollow portion, and there being a passage for the cooling medium from the outer chamber to the hollow of the stationary drum whereby a supply of cooling fluid from a single source is furnished both the outer and inner cooling 115 chamber.

2. A gas engine comprising a main casing having a gas inlet and an exhaust, and opposite rotary abutment valve extensions, a double headed abutment valve in each ex- 120

tension; a stationary drum within and concentric with the casing body, a main shaft, a piston structure thereon comprising circular ends connected by opposite pistons adapted to travel in the space between the casing and drum, and to pass said abutment valves, a compression chamber over one of said abutment valve extensions, means for controlling entrance to and exit from the compression chamber, an explosion chamber behind one of the pistons, means for exploding gas drawn from the compression chamber to the explosion chamber on the opposite side from the inlet of the abutment valve, and outer walls forming a chamber for a cooling medium around the main casing body, the stationary drum having a hollow portion, and there being a passage for the cooling medium from the outer chamber to the hollow drum.

3. An engine comprising a main body casing, an inner fixed drum, a fixed sleeve supported by the casing and passing through the drum, a shaft passing through said sleeve, a piston structure having circular ends connected by opposite pistons movable in the space between the casing and the drum, outer walls forming an outer cooling chamber around the main casing, said drum having a hollow portion, and there being a passage within said sleeve for the cooling medium from the outer chamber to the hollow of the drum.

4. A gas engine comprising a casing having end flanges and side flanges, rings closing the spaces between the end flanges, and plates connecting the said flanges whereby an extended cooling chamber is formed, a fixed inner drum having a hollow portion, there being a passage between said extended chamber and the hollow of the drum whereby a supply of cooling fluid from a single source is furnished both the outer and inner cooling chamber, opposite pistons movable between the casing and drum, there being a gas inlet and an exhaust ad-

jacent a compression chamber, means for controlling gas inlet to and outlet from said chamber, and a cooling medium inlet and outlet.

50

5. A gas engine comprising a casing, a wall forming an outer cooling chamber, an inner drum having a hollow portion and also end grooves, said outer chamber, hollow portion and grooves being connected, a piston structure having circular ends connected by opposite pistons, said ends having holes communicating with said grooves whereby the cooling medium can pass to the outer sides of said ends, there being suitable inlet and outlet openings for the cooling medium.

60

6. A gas engine comprising a casing, a central sleeve within said casing and supported thereby, a shaft in the sleeve, a hollow drum fixed on the sleeve, the drum having also end grooves, there being a passage for a cooling medium along the shaft to the hollow of the drum and thence to the end grooves and to an outlet.

70

7. A gas engine comprising a casing having abutment valve extensions, abutment valves therein, a central drum, an outer wall forming a compression chamber over one of the abutment extensions, said chamber being connected to the space between the casing and drum through the abutment valve chamber on the inlet side, such connection being controlled solely by the abutment valve, said chamber being connected to the space between the casing and drum on the explosion side of the abutment valve, the latter connection being controlled by the abutment valve and by a separate suitably timed valve.
